[57] CLAIM

The ornamental design for a pool cover roller, substantially as shown and described.

DESCRIPTION

FIG. 1 is an isometric view of a pool cover roller showing my new design;

FIG. 2 is a front elevation view of the pool cover roller of FIG. 1;

FIG. 3 is a rear elevational view of the pool cover roller of FIG. 1;

FIG. 4 is an elevational view showing one end of the pool cover roller of FIG. 1;

FIG. 5 is an elevational view showing the end opposite the one end of FIG. 4;

FIG. 6 is a top plan view of the pool cover roller of FIG. 1;

FIG. 7 is a bottom plan view of the pool cover roller of FIG. 1; and

FIG. 8 is an isometric view showing a modified form of the pool cover roller of FIG. 1 having no wheels.
